UNITED STATES PATENT OFFICE.

JAMES H. BRADLEY, OF DENTON, MONTANA.

TOY RAILROAD.

1,367,232.

Specification of Letters Patent. Patented Feb. 1, 1921.

Application filed February 24, 1920. Serial No. 360,791.

To all whom it may concern:

Be it known that I, JAMES H. BRADLEY, a citizen of the United States, and a resident of Denton, in the county of Fergus and 5 State of Montana, have invented certain new and useful Improvements in Toy Railroads, of which the following is a specification.

My invention is a simple and inexpensive 10 device which will be a source of pleasure to children, while developing their power of concentration.

Stated generally the invention comprises a teeter board over which a wheeled figure 15 is caused to roll by the tilting of the board.

An embodiment of the invention is illustrated in the accompanying drawings in which—

Figure 1 is a plan view and

20 Fig. 2 a side view of the device arranged for use.

Fig. 3 is a side view showing the board folded; and

Fig. 4 is a detail plan view of a deflector.

25 The board consists of two similar oblong plates 1 and 2; connected at their meeting ends by hinges 3, and provided at their outer free ends with upstanding strips or stop rails 4. Links 5 are pivoted at their upper ends to the edges of the board members 1 and 2 and at their lower ends are pivoted to each other, the pivot 6 being a tightly fitting rivet whereby the frictional engagement between the opposed faces of 30 the links will tend to hold them in a set position and prevent collapse of the toy while it is in use. It will be readily noted that when the device is not in use it may be folded into a small space as shown in 35 Fig. 3 and when set up for use the links serve as a fulcrum or rocker for the board as well as a lock or brace to prevent folding thereof.

On the upper side of the board are strips 45 7, representing rails and defining a plurality of tracks, 8, 9, 10 and 11, extending from end to end of the board. At one end of the board may be placed a symbol 12, indicating a station, and at the opposite end of the 50 board may be placed a symbol 13, indicating a roundhouse, the symbols being in diagonally opposite corners as shown.

Intermediate the ends of the board members 1 and 2, reversely curved strips 14 and 55 15 are placed within the tracks 9 and 10, to represent switch rails and similar strips or

rails 16 are placed within the tracks 8 and 11, it being noted that the ends of all said switch rails are spaced from the adjacent track rails. Some of the tracks are interrupted, as at 17, and cross-over switch rails 18, extend between adjacent tracks at the points of interruption. Each cross over rail forms a point with one track rail but merges smoothly into the adjacent track rail and continuity of travel in a straight line is provided by the short track rail sections 19, between the rails 18. At the entrance of each switch or cross-over, I provide within each track a deflector or guard 20 which 60 consists of a flat substantially T-shaped plate, the head having a convex edge 21 and the stem having a longitudinal slot 22 through which a securing screw 23 is inserted into the board so that the deflector 65 or guard may be adjusted toward or from a track rail and also set so as to present either end to the track rail.

A rolling object, such as a toy locomotive, 70 as shown at 24, is provided to run on the tracks and this object, might of course well be any character of wheeled toy.

The object to be attained in using the toy is to cause the locomotive to run from the station to the round house or vice versa and 75 this is accomplished by tilting or rocking the board after setting the guards or deflectors so that some of the switches will be open and others closed. For example, assuming the board to be in the position shown in Fig. 2, 80 and the locomotive to be placed at the station 12, the locomotive will roll to the opposite end of the track 8, where it will be stopped by the rail 4. The board is then 85 rocked so as to tilt in the opposite direction 90 whereupon the locomotive will start a return trip on the track 8, but, if the deflectors have been properly set the locomotive will 95 be turned aside over one of the switches and caused to run onto the track 9 and it will 100 be understood that the locomotive may be shifted at either switch according to the manner in which the deflectors are set. When the board is again rocked, the locomotive will travel the length of the track 9, 105 being subsequently in the same manner shifted to the tracks 10 and 11 successively and passing along the latter to the roundhouse. Obviously by properly setting the deflectors the locomotive may be caused to 110 travel from the roundhouse to the station. The device is exceedingly simple and inex-

pensive and contains nothing whatever that is apt to get out of order or misplaced.

Various modifications and changes may be made in the form of the device one embodiment of which is shown in the accompanying drawing, without departing from the spirit and scope of the invention, and as set forth in the claims hereto appended, such for instance as the making of the device in one piece instead of foldable, or the entire device might be made of one piece of metal with the tracks formed therefrom and integral therewith, and various other modifications all of which would be included within the scope of the appended claims.

Having thus fully described my invention, what I claim as new and desire to secure by Letters Patent of the United States, is—

20 1. A toy comprising a sectional board, a foldable brace attached to adjacent sections of the board and forming a rocker for the same when extended, and a rolling object to travel on the board.

25 2. A toy comprising a board consisting of similar sections hinged together at their meeting ends, links pivoted together and having their free ends pivoted to the edges of the sections adjacent and at opposite 30 sides of the hinged connection between the same, the combined length of the links being greater than the distance between their points of attachment to the sections of the board, whereby when the board is extended 35 the links will form a fulcrum therefor, and a rolling object to travel on the board.

3. A toy comprising a board consisting of sections hinged together at their meeting

ends, means on which said board is adapted to rock, tracks extending from end to end of the board, goals at diagonally opposite points of the board, switches connecting adjacent tracks, and means on the board to guide the object along the tracks or onto the switches.

4. A toy comprising a board consisting of sections hinged together at their meeting ends, means on which said board is adapted to rock, tracks on the board, switches connecting adjacent tracks, deflectors on the board within the tracks adjacent the switches, and a rolling object to run on the tracks.

5. A toy comprising a board consisting of sections hinged together at their meeting ends, means on which said board is adapted to rock, tracks on the board, switches connecting adjacent tracks, stop rails at the ends of the board, and a rolling object to travel on the tracks and switches.

6. A toy comprising a board, means on which said board is adapted to rock, strips on the board forming tracks and switches, deflectors at the entrances of the switches adjustable transversely and pivotally and a rolling object to travel on the said strips.

7. A toy comprising a board, means on which said board is adapted to rock, strips on the board forming tracks and switches, a rolling object to travel on said strips, and deflectors at the entrances to the switches each consisting of a substantially T-shaped plate, the head of the T having a convex edge and the stem having a longitudinal slot through which a fastening is inserted into the board.

JAMES H. BRADLEY.
